(57) **CLAIM**

The ornamental design of a clothing article rack, as shown and described.

DESCRIPTION

FIG. 1 is a perspective view of a clothing article rack of my new design;

FIG. 2 is a top view of the design of FIG. 1;

FIG. 3 is a bottom view of the design of FIG. 1;

FIG. 4 is a side view of the design of FIG. 1;

FIG. 5 is an opposite side view of the design of FIG. 1;

FIG. 6 is a front view of the design of FIG. 1; and,

FIG. 7 is a rear view of the design of FIG. 1.

The broken lines, if any, represent portions of the structure that form no part of the claim.
